J. B. GARRETT.

FILM ENVELOP.

APPLICATION FILED AUG. 24, 1920.

1,393,109.

Patented Oct. 11, 1921.

UNITED STATES PATENT OFFICE.

JOHN B. GARRETT, OF TROY, NEW YORK.

FILM-ENVELOP.

1,393,109.

Specification of Letters Patent.

Patented Oct. 11, 1921.

Application filed August 24, 1920. Serial No. 405,740.

To all whom it may concern:

Be it known that I, JOHN B. GARRETT, a citizen of the United States, residing at Troy, in the county of Rensselaer and State of New York, have invented certain new and useful Improvements in Film-Envelops, of which the following is a specification, reference being had therein to the accompanying drawing.

10 The invention relates to film envelops and has for its object to provide a device of this character so constructed that it may be disposed over a developing tank and members carried by the developing tank 15 connected to cross cords extending through the envelop and attached to the film and forming means whereby the envelop may be severed and the film drawn into the developing tank. Also to provide a member extending upwardly from the film through the envelop and forming means whereby after the film has been drawn into the developing tank, it may be removed from the tank, 20 after the envelop has been discarded.

25 A further object is to provide a film envelop or container particularly adapted for use in connection with a developing tank of the character set forth in my application for patent filed August 24th, 1920, Serial 30 No. 405,739.

35 A further object is to provide a film envelop, particularly adapted for use in connection with a daylight developing tank and particularly in connection with X-ray films. 40 The envelop comprises an inner and an outer envelop, one disposed within the other, the inner envelop being formed from a light proof material, preferably black and adapted to receive a film. Also to provide 45 envelop cutting flexible members connected to the film and crossed and extending through the lower corners of the film envelop and through the corners of the outer envelop, the ends of said severing members 50 being provided with members adapted to be engaged by members within the tank whereby a downward pull may be imparted on the severing members for severing the envelops and drawing the film into the developing tank.

55 A further object is to provide the inner envelop with a flap which may be disposed over the upper edge of the outer envelop and forming means whereby the inner envelop may be held against downward movement during a severing operation.

With the above and other objects in view the invention resides in the combination and arrangement of parts as hereinafter set forth, shown in the drawings, described and claimed, it being understood that changes in the precise embodiment of the invention may be made within the scope of what is claimed without departing from the spirit of the invention.

60 In the drawings:—

Figure 1 is a plan view of the envelop, parts being broken away to show the structure.

Fig. 2 is a vertical sectional view through a daylight developing tank illustrating the method whereby the film is drawn from the envelop.

Fig. 3 is a perspective view of the flexible member disposed in the tank by means of which the film is drawn from the envelop.

Fig. 4 is an enlarged sectional view taken on line 4—4 of Fig. 1.

Referring to the drawings, the numeral 1 designates the outer envelop and 2 the inner envelop. The inner envelop is made from a light resisting material and is preferably black, while the outer envelop may be made from any kind of material. The inner envelop 2 is provided with a flap 3, which flap 80 during a film removing operation is disposed over the upper edge 4 of the outer envelop as shown at 1, the purpose of which will presently appear. The film 5, after an exposure, is connected to the cords 6 as at 85 7 by means of clips or in any other manner and is then placed in the inner envelop 3. The severing cords 6 are crossed as at 8 and extend through the corners 9 of the inner envelop 2, and extend downwardly through 90 the open corners 10 of the outer envelop 1, said severing cords terminating in rings 11. When it is desired to develop the film, the envelops are disposed in the upper V-shaped slot 12 of the developing tank 13 as shown 95 in Fig. 2, with the rings 11 in the developing compartment 14, that is after the hooks 15 of the flexible withdrawing members 16 have been hooked in the rings 11, this being accomplished by the removal of the cover 100 17 of the tank. The flexible withdrawing members 16 extend downwardly through the developing compartment 14 and thence upwardly through the compartment 18, and are connected to a bar 19, which bar is 105 grasped by the hand of the operator so that a downward pull may be imparted on the

110

severing cords 6 so that the lower ends of the envelops 1 and 2 may be severed and the film 5 drawn into the developing compartment 14. During this withdrawing operation, the other hand of the operator is in engagement with the flap 3 of the envelop 2 so as to prevent downward movement of the envelop 2.

Secured to the upper end of the film 5 as 10 at 20 is a cord 21, which cord extends through an aperture 22 in the upper end of the envelop 2 and is of sufficient length that after the film has been drawn into the developing compartment 14 and the envelops 15 discarded, the end 23 of the string 21 will extend above the V-shaped slot 12, thereby allowing the operator to withdraw the film from the developing compartment after a developing operation. The string 21 may 20 be wound around the disk fastener 24 when the film is not being developed, thereby preventing the inner envelop 2 from coming out of the outer envelop 1.

From the above it will be seen that a film 25 envelop is provided, which is so constructed that it may be used in connection with a daylight developing tank when it is desired to develop the film within the envelop.

The invention having been set forth what 30 is claimed as new and useful is:—

1. A film container comprising an envelop adapted to receive a film, crossed envelop severing members disposed in the lower end of the envelop and having their ends connected to a film, said severing members having 35 their other ends extending through the envelop and provided with attaching means.

2. A film container comprising an envelop adapted to receive a film, crossed flexible 40 members disposed in the lower ends of the envelop and having their ends connected to a film, said flexible members having their other ends extending through the envelop

and provided with attaching members and a flexible member extending through the 45 upper end of the envelop and having its end attached to the film.

3. A film container comprising an envelop disposed within an envelop, crossed flexible members disposed in the lower end of the 50 inner envelop and having their ends connected to a film, the other ends of said crossed members extending through the corners of the inner and outer envelop and terminating in attaching members, a string extending through the inner envelop and having its end connected to the film within the 55 inner envelop.

4. A film container comprising an envelop disposed within an envelop, crossed envelop 60 severing members disposed in the lower end of the inner envelop and having their ends connected to a film, the other ends of said crossed members extending through opposite corners of the inner and outer envelopes 65 and terminating in attaching members.

5. A film container comprising an envelop adapted to receive a film, a pliable member disposed in the lower end of the envelop and having its end connected to the film 70 adjacent one side thereof, the other end of said pliable member extending through the opposite corner of the envelop and terminating in an attaching member.

6. A film container comprising an envelop 75 disposed within an envelop, pliable members connected to the film adjacent its sides, said pliable members extending through the corners of the envelops at opposite points to their points of attachment to the film, and 80 a pliable member connected to the upper end of the film and extending through the upper end of the inner envelop.

In testimony whereof I hereunto affix my signature.

JOHN B. GARRETT.
